ELECTRIC SWITCH

William Sharp, Birmingham, England

Application April 14, 1949, Serial No. 87,443
In Great Britain May 4, 1948

3 Claims. (Cl. 206—116)

1

This invention relates to electric switches and particularly to starter switches for electric motors, and this invention has for its object to provide means contributing to a simplified construction of the switch of the aforesaid type which is of compact formation.

A further object of the invention is to provide means utilizing the moving contacts of the switch as spring member for opening the switch arm, thus avoiding the use of independent springs and the possibility of the switch not opening by breakage of springs.

A further object of the invention is the provision of means making use of the construction of a thermostatically operated catch which is held in the catch position by the spring member forming the moving contacts.

A still further object of the invention is to provide means leading to a simple form of thermostatically operated catch release coacting directly with the switch arm.

Referring to the drawings:

Figure 1 is a plan of the switch body with the switch arm opened out.

Figure 2 is a section on line II—II of Figure 1, but showing the switch closed and showing the switch casing in broken lines.

Figure 3 is a side elevation of the switch body.

Figure 4 is a plan view of the catch on the switch arm.

According to a convenient embodiment of this invention, the switch comprises a rectangular insulating base 1 which has three parallel channels 2 formed thereacross. A spring contact blade 3 is mounted in each channel at one end and each contact blade comprises a Z-shaped strip of spring metal which is fixed to the base 1 and has a circuit mains terminal 4 thereon for fixing thereto a lead wire of the electric supply. The spring contact blade 3 is conveniently formed of Phosphor bronze. The fixed contacts 5 comprise metal strips fixed inside the channels 2, one end of the strip being L-shaped to form a raised step for contacting with the spring contact blade 3. One arm of an L-shaped bi-metal strip 6 is fixed under each contact strip 5 by means of the terminal screw 7 which fixes the contact strip 5 to the base 1. A heating wire 8 is coiled around an insulating sleeve 9 on the bi-metal strip, and one end of this wire 8 is connected to a circuit mains terminal 10 for a lead wire of the electric motor circuit and to the contact strip 5 by the screw 7. The switch arm 11 is mounted on bifurcated lugs 12 on each side of the insulating base 1, and such arm has three

2

projections 13 adapted to bear on the spring contact blades 3 and press the same on the fixed contacts 5. A trip catch lever 14 is pivotally mounted on the base and comprises a U-shaped wire member having an insulating sleeve thereon for contacting with the bi-metal strips 6. The trip catch lever is normally urged inwardly towards the bi-metal strips 6 by the spring 15. The switch arm has an adjustable catch projection 16 which when the switch arm is being closed is adapted to bear against the roller on the trip catch lever and press it rearwardly so that the trip catch lever will engage over the projection 16 and hold the switch arm in the "on" position. The base 1 is mounted in a box 17 and two plungers or press buttons 18 and 19 are mounted on the cover 20, one plunger 19 being adapted to bear on the switch arm 11 to close the switch, whilst the other plunger 18 when depressed bears against and pivots the trip catch lever 14, so that the switch arm will automatically open by the pressure of the contact blades 3. The trip catch lever can also be moved by the bi-metal strips. If the bi-metal strip is overheated it is deflected against the trip catch lever 14 and moves the same from the projection, thereby throwing the switch open. By adjusting the projection 16, the particular condition when the switch will automatically open can be varied.

In order to prevent the switch being closed until the bi-metal strips have assumed their normal position, a stop lever 21 is pivoted on the base 1 and connected by the helical spring 22 to the trip catch lever 14. When therefore the trip catch lever 14 is moved by the bi-metal strips, the lever 21 will be pivoted therewith to lie in the path of a projection 23 on the arm 11, thereby preventing such arm being depressed. The spring 22 forms an expansible link and permits the catch lever 14 to be moved to engage over the projection 16 whilst the projection 23 lies in front of the lever 21. The coils of the spring are normally closed to form a solid link to push the lever 21 rearwardly by the spring pressure of the lever 14.

Having thus described the invention, what is claimed as new and desired to be secured by Letters Patent, is:

1. An electric switch comprising an insulating base, a plurality of fixed contacts on the base, each fixed contact being electrically connected to a circuit mains terminal, a plurality of movable contacts mounted on the base and each comprising a blade spring forming an arm flexibly connected at one end to said base, each blade

spring forming an electric conductor and being electrically connected to another circuit mains terminal, a switch arm pivotally mounted on said base and provided with projections adapted to bear against said arms of the movable contacts and to depress the said movable contacts into contact with the said fixed contacts, said movable contacts being adapted to be urged to open position by the spring pressure of the said movable contacts on said projections, a trip lever comprising a transverse bar having legs at each side which are pivotally mounted on said base, a catch projection on the pivoted switch arm which is engaged by the trip lever and held in engagement by said blade springs, bi-metal strips which lie in front of said transverse bar and which when deflected pivot the trip lever to release said switch arm when an overcurrent passes through one or more of the bi-metal strips, a first press button adapted to bear on said switch arm to thereby move said catch projection into engagement with the trip lever, and a second press button adapted to bear against and operate the trip lever to release the switch arm.

2. An electric switch comprising an insulating base, a plurality of fixed contacts on said base, each fixed contact being electrically connected to a circuit mains terminal, a plurality of movable contacts mounted on the base and each movable contact comprising a Z-shaped blade spring having a straight arm and a double-bend at its inner end for connection to the base and forming an electric conductor and electrically connected to another circuit mains terminal, a switch arm pivotally mounted on said base and provided with projections adapted to bear against said arms of said movable contacts and to depress said movable contacts into engagement with said fixed contacts and by flexing said straight arms inwardly between said fixed contacts and the double-bend at the fixed ends of the blade springs and to be urged in the open position by the spring pressure of said movable contacts on said switch arm projections, a trip lever comprising a transverse bar arranged parallel to the axis of said switch arm and having legs at each side which are pivotally mounted on said base, a catch projection on the pivoted switch arm which is engaged by said transverse bar of the trip lever and held in engagement by said blade springs, one or more bi-metal strips lying in front of the said transverse bar and adapted to deflect and to thereby pivot the trip lever to release said switch arm when an overcurrent passes through one or more of said bi-metal strips, a first press button adapted to bear on the switch arm to thereby move the catch projection into engagement with the trip lever,

and a second press button adapted to bear on the transverse bar of the trip lever for moving the same to release the switch arm.

3. An electric switch comprising an insulating base, a plurality of fixed contacts on the base, each fixed contact being electrically connected to one circuit mains terminal, a plurality of movable contacts mounted on the base, each movable contact comprising a blade spring shaped to form a straight arm and a double-bend at its inner end for connection to the base and forming an electric conductor connected to another circuit mains terminal, a switch arm pivotally mounted on said base and provided with projections adapted to bear against said straight arms of said movable contacts and to depress said movable contacts into contact with said fixed contacts and by flexing the straight arms inwardly between the fixed contacts and the double-bend at the fixed ends of the spring blades and to be urged in the open position by the spring pressure of said blade springs of the movable contacts on said projections, a trip lever comprising a transverse bar arranged substantially parallel to the axis of said switch arm and having lugs at each side which are pivotally mounted on said base, a catch projection on the pivoted switch arm which is engaged by said transverse bar of the trip lever and held in engagement by said spring blades, bi-metal strips lying in front of said transverse bar of the trip lever and adapted to deflect to thereby pivot the trip lever for release of the switch arm when an overcurrent passes through at least one of said bi-metal strips, a first press button adapted to bear on the switch arm to move said catch projection into engagement with the trip lever, a second press button adapted to bear on the transverse bar of the trip lever for moving the same to release the switch arm, and a stop device comprising a pivoted lever connected to said bi-metal strip by means of a helical spring, so that when said bi-metal strip is flexed by overload current, said pivoted lever is moved into position to form a stop preventing the pivoted switch arm being moved into the "on" position until said bi-metal strip assumes its normal position.
